Primary Examiner — Clare E Heflin(74) *Attorney, Agent, or Firm* — Chin Lim**CLAIM**

The ornamental design for a light fixture, as shown and described.

DESCRIPTION

FIG. 1 is a front perspective view of the light fixture of the present invention;

FIG. 2 is a top plan view of the light fixture of FIG. 1;

FIG. 3 is a front view of the light fixture of FIG. 1, wherein the

back, left, and right views are the same; and,

FIG. 4 is a bottom plan view of the light fixture of FIG. 1.

The broken line showing an electrical control module forms

no part of the claimed design.
